CLAIM

I claim the ornamental design for a storage module for a video editing system, as shown and described.

DESCRIPTION

FIG. 1 is a top, front and left side perspective view of a storage module for a video editing system showing my new design;

FIG. 2 is a left side elevational view thereof, the right side elevational view being a mirror image with exception of the showing of the three indentations from the front right face;

FIG. 3 is an enlarged elevational view thereof;

FIG. 4 is an enlarged elevational view thereof;

FIG. 5 is top plan view thereof; and,

FIG. 6 is a bottom plan view thereof.
